ABSTRACT

The invention is a wall insulator adapted to be used in conjunction with a bed or the like when the bed is placed against a wall. The invention prevents a user of the bed from coming into contact with the wall but rather a padded insulated surface.

12 Claims, 2 Drawing Sheets

BEDSIDE WALL INSULATOR

FIELD OF THE INVENTION

The instant invention relates to removable wall coverings adapted to be placed next to a bed or the like so as to prevent a user of the bed from contacting the wall.

BACKGROUND OF THE INVENTION

For many years, people, who due to space constraints have placed their bed lengthwise against a wall, have suffered from a recurring problem; especially, in colder climates, a sleeper would, upon performing the various motions associated with sleep, come in contact with a cold wall. This contact would have several unwanted effects. The first of which would be the awakening of the sleeper thereby effectively preventing a complete night's sleep. Secondly, should the sleeper not be awakened by such contact, and remain in contact with the cold adjacent wall, various muscular spasms could develop, rendering the sleeper, at the very least sore and stiff upon awakening.

The instant invention provides a solution to these problems. An insulating member is releasably attached to the cold wall by means of a novel affixment. This allows for facile installation by virtually anyone. The insulative member is covered by a removable contact surface which, as will be further described, would be adapted to provide a comfortable surface against which the sleeper can rest. Furthermore, the present invention contemplates the removability and washability of the contact surface so as to maintain sanitation.

Exemplary of prior inventions relating to accouterments adapted for use with beds include:

U.S. Pat. No. 1,282,281 to Pennington discloses a planar member adapted to be attached to an open tubular bedstead;

U.S. Pat. No. 2,375,941 discloses a sound-reducing device for beds which comprises a plurality of hinged panels configured so as to be able to essentially enclose a bed from the surrounding room;

U.S. Pat. No. 4,878,259 to Casey discloses a modular energy-saving covering which comprises an insulating fiber sandwiched between two sheets. These sheets are then attached via snaps or strings to each other so as to provide for a plurality of the sheets to form a substantially planar covering over the object to be insulated.

As can be seen, none of these devices solves the specific problem of contacting a wall disposed longitudinally adjacent a bed.

OBJECTS OF THE INVENTION

It is an object of the invention to provide an insulative wall covering adjacent a bed or the like. It is another object of the invention to provide for an insulating wall covering which is easily installed. It is a further object of the invention to provide for an insulating wall covering which is robust. It is another object of the invention to provide for an insulating wall covering having a removable contact surface. It is another object of the invention to provide an affixment therefor which serves to retain the wall covering in its preferred location whilst allowing for easy removal thereof. It is a further object of the invention to provide a soft resilient surface for a user to rest against. These and other objects of the invention will become apparent from the detailed description of the preferred embodiment, drawings and claims appended hereto.

BRIEF DESCRIPTION OF THE DRAWINGS

FIG. 1 is a perspective view of the invention as used; FIG. 2 is an exploded view of the invention; and FIG. 3 is an edge-on view of the affixment and bracket.

DETAILED DESCRIPTION OF THE PREFERRED EMBODIMENT

The instant invention comprehends a panel **10** which is disposed on a wall **15** so as to be longitudinally parallel to a bed or other furniture **20** which is located adjacent thereto. Panel **10** further includes an insulative member **25** which in the preferred embodiment is foamed polystyrene or other plastic having insulating properties or alternatively a sheet or cardboard **35** having faveform or honeycomb shaped corrugations **30** thereon. The choice of material or alternatives thereto is based on the combined requirements of rigidity and insulation. Surrounding the insulative member or core **35** is a layer of resilient padding **40**. This padding **40** provides a comfortable subsurface for a user of bed **20** to rest against. Surrounding resilient pad **40** is a removable contact surface **45** which, in the preferred embodiment, is a fabric. The fabric contact surface **45** is chosen for comfort as well as washability as this is the surface that the bed user actually contacts when against the invention. Furthermore as the contact surface **45** is not integral with the panel **10** nor the resilient pad **40**, the choice of material used for the outer cover or contact surface **45** is amenable to aesthetic choices. The outer cover or contact surface **45** is retained about panel **10** by an elastic strap **50** disposed on the rear side **55** of panel **20** and attached to outer cover **45**. The elastic strap **50** is so disposed to draw outer cover **50** about the bottom **60**, first end **65**, and second end **70** of panel **10**.

The top end **72** of the panel **10** is surmounted by a resilient affixment **75** and is attached thereto. In the preferred embodiment panel **20** is glued to affixment **75** by use of an adhesive appropriate to the panel **10** and affixment **75** material.

Affixment **75** comprehends a backplate **80** which, when installed, is coplanar to the top end **72** of the panel **10**. Depending from the backplate **80** and integral thereto, is rib **85**. Rib **85** is extensive outwardly from backplate **80** and is disposed to come into coplanar contact with the rear side **55** of panel **10**. Looking rearwardly from backplate **80** attachment tang **90** depends therefrom. Tang **90** comprehends an interior side **95** which is disposed toward rib **85**. At the distal end of the interior side **95** of tang **90** resides an inwardly extensive lateral extension **100**. Lateral extension **100** plays a thickening of tang **90** as the distal end of the tang **90** is approached. Furthermore, tang **90** is biased toward rib **85** thereby defining a capture pocket **105** between tang **90** and rib **85**.

Bracket **110** is disposed along the wall **15** and attached thereto by fasteners **115** inserted through mounting holes **120** defined therein. The bracket **110** has defined thereon a top bracket edge **125**, a bottom bracket edge **130** and a first bracket side **135** and a second bracket side **140**. Disposed longitudinally along the top bracket edge **125** is a receiving groove **145**. The receiving groove **145** is in the presently preferred embodiment formed by a first plane **150** disposed parallel to the top bracket edge **125** and interior thereto, and a second plane **155** disposed at an acute angle to the first plane **150**, thereby forming receiving groove **145** therebetween. Functionally, bracket **110** would be mounted to wall **15** as aforescribed with the receiving groove **145** disposed toward the wall **15** and oriented at the top of the bracket **110**.

Cover or contact surface **45** is placed about panel **10** and affixment **75**, covering capture pocket **105**. Panel **20** is then placed at the wall **15** with affixment **75** disposed along the top edge thereof over bracket **110**. Panel **20** is then lowered onto bracket **110** until tang **90** snaps into receiving groove **145** and the top bracket edge **125** is sealed in capture pocket **105**. As tang **90** is inwardly biased, the panel **20** is now affixed to the bracket **110** and cover or contact surface **45** is trapped between the top bracket edge **125** and capture pocket **105**, thereby retaining cover **45** and panel **20** to bracket **110** and, therefore to wall **15**.

The above recited description of the presently preferred embodiment is illustrative of the instant invention and should not be construed to incur limitations regarding the invention to any extent greater than recited in the claims herebelow.

In accordance with my invention, I claim:

1. A wall insulator comprising an insulating panel and a bracket wherein said panel is faviform and is covered by an elastically retained contact surface and has a pad placed between said faviform panel and said contact surface, and is engaged to said bracket and is suspended therefrom and a means for engaging said panel to said bracket wherein said means for engaging said panel to said bracket has a top edge and a receiving groove receiving said panel with said receiving groove being defined by a first planar surface and a second planar surface and said first planar surface and said second planar surface define an acute angle therebetween so as to capture said panel within said acute angle.

2. The invention according to claim 1, wherein said bracket further comprises a top edge receiving said means for engaging said panel to said bracket.

3. The invention according to claim 1, wherein said means for engaging said bracket further comprises an affixment having a rib and a tang dependent therefrom.

4. The invention according to claim 3, wherein said rib and tang define a capture pocket therebetween which captures said top edge of said bracket.

5. The invention according to claim 3, wherein said tang has a distal end having a lateral extension directed inwardly toward said capture pocket.

6. An insulating device adapted to be attached to a wall adjacent an object or furniture so as to prevent contact between a user of said object or furniture and said wall comprising a faviform panel surrounded by a removable contact surface wherein said contact surface is elastically retained on said faviform panel and a bracket, removably engaged to said faviform panel wherein said bracket further comprises a first surface and a second surface and said faviform panel further comprises an affixment having a receiving groove defined by said first surface and said second surface, and a tang and a rib which extends into said groove thereby removably affixing said panels to said bracket.

7. The invention according to claim 6, wherein said affixment further comprises a backplate having said tang dependent therefrom.

8. The invention according to claim 7, wherein said tang has a distal end and which displays a lateral extension.

9. A wall insulator adapted to be used in conjunction with a bed, said bed being located adjacent to a wall, said insulator comprising a rigid panel having thermal insulating properties, by means of said panel having faviform construction and a bracket receiving said panel wherein said panel is extensive along said bracket and is releaseably affixed thereto by means of said bracket having a first surface and a second surface with said first surface and said second surface defining an acutely angled receiving groove therebetween and said panel is inserted into said groove and retained therein; said panel being covered by a pad and a contact surface, wherein said contact surface is removable from said panel.

10. The invention according to claim 9, wherein said panel is formed of foamed polystyrene.

11. The invention according to claim 9, wherein said contact surface is elastically retained about said panel.

12. The invention according to claim 11, wherein said panel further comprises an affixment having a tang which is compressively received by said groove.
